UNITED STATES PATENT OFFICE.

JOHN C. MUNDY, OF PHILADELPHIA, AND HARRY T. WILSON, OF TULLYTOWN, PENNSYLVANIA.

EXCAVATING APPARATUS AND DRAG BUCKET.

1,420,733.

Specification of Letters Patent. Patented June 27, 1922.

Application filed February 12, 1921. Serial No. 444,464.

To all whom it may concern:

Be it known that we, JOHN C. MUNDY and HARRY T. WILSON, citizens of the United States, residing at Philadelphia and Tullytown, in the counties of Philadelphia and Bucks, respectively, and State of Pennsylvania, have invented certain new and useful Improvements in Excavating Apparatus and Drag Buckets, of which the following is a 10 specification, reference being had to the accompanying drawings.

The purpose of the present invention is to provide an excavating apparatus including a drag bucket to facilitate excavating generally, and to provide a device of such a character as to consume less head-room for dumping purposes, and at the same time allowing for less clearance above the dump car, and also to provide an apparatus which 15 is simple and inexpensive in operation, and wherein the drag bucket is capable of swinging back and forth readily.

Another purpose consists in the provision of a drag bucket, which can be placed close 20 to the car and held steady, also allowing the bucket to be swung over the car and opened slowly, permitting the load to drop into the car without a rush or splash of the excavated material.

30 In devices of this character heretofore used, the dumping of a load in a dump car cannot be accomplished without spilling the material over the ground, on account of the distance the material necessarily has to drop from the bucket to the car, and also on account of the excessive swinging motion, and it is the aim of the present invention to overcome these disadvantages.

A further purpose is to provide a drag 40 bucket for excavating machine of the present character, wherein the bucket comprises two hingedly united sections, so put together that while the bucket is held in an engaging position with the ground through means of 45 a pulling cable, the other section is held closed by another pulling cable, there being means for opening the bucket by separating the sections, after the first and second cable hoists the bucket and after the first cable 50 is held taut and the second cable relaxed, the opening section of the bucket being so relatively disposed with regard to the other section, that the bucket may be disposed adjacent the top of the dump car, and yet 55 permit the opening section to open readily,

to prevent the material from discharging without splashing and spilling on the ground.

Still a further purpose is to provide an 60 improved drag and dump bucket.

While the design and construction at present illustrated and set forth is deemed preferable, it is obvious that as a result of a reduction of the invention to a more practical form for commercial purposes, the invention may be susceptible of changes, and the right to these changes is claimed, provided they are comprehended within the 65 scope of what is claimed.

The invention comprises further features 70 and combination of parts, as will be herein-after set forth, shown in the drawings and claimed.

In the drawings:

Figure 1 is a view in side elevation of the 75 improved excavating machine as a whole, showing the lifting boom in a raised position, and the drag bucket elevated, with the bucket open.

Figure 2 is a view in side elevation of a 80 portion of the boom supporting frame, showing the boom in a requisite lowered position, with the drag bucket in operative engagement with the ground.

Figure 3 is an enlarged detail view in side 85 elevation of the drag bucket.

Figure 4 is a top plan view of the drag bucket.

Figure 5 is a plan view of the controlled 90 hoisting of the apparatus, for operating the cables.

Figure 6 is a plan view of the upper front 95 end of the machine showing the shaft 20 and the wheel 21.

Figure 7 is a sectional plan view on line 7—7 of Figure 1.

Figure 8 is a sectional view on line 8—8 of Figure 1.

Figure 9 is a detail view of the bail straps 100 44, showing the brace 48.

Referring more especially to the drawings, 1 designates a portable frame, which is mounted upon suitable forward and rear supporting wheels 2 and 3. These wheels may be of a character to operate on the 105 ground, or may be of the character to operate on tracks.

A conventional form of engine 4 is mounted upon the frame, and in the bearings on the frame a hoisting shaft 5, which has a 110

master gear 6 connecting with the engine mechanism. Carried by the shaft 5 is a plurality of power winding drums 7, 8 and 9, there being suitable clutch mechanisms 10 for gearing one or more of the drums through the shaft, in order to operate the several hoisting cables in the proper manner for excavating.

By means of a coupling 11, to which a lifting boom 12 is pivotally connected at 13, said lifting boom is connected to the forward portion of the frame 1, so that the boom can swing laterally. The coupling member 11 is pivoted to the frame 1 as at 14, so that the coupling member can move pivotally in a horizontal plane, while through the medium of the pivot 13, the boom is capable of moving in a vertical plane. While the coupling 11 is mounted to move pivotally in a horizontal plane, so that the boom 12 may swing or turn upon a vertical axis, it is the purpose to operate the boom in a direction substantially direct from the rear of the portable frame 1. However any well known conventional means (not shown) may be employed for turning the boom on its vertical axis and for holding the boom against turning on such axis.

The boom proper carries a plurality of pulleys 15, 16 and 17, and mounted in the projecting members 18 of the boom is a pulley 19. Mounted on a shaft 20 which is carried by the frame 1, is a pulley 21, and operatively connected with the pulley 21 is a hoisting chain 22, which passes over the pulley 19, and thence over the pulley 23. This chain also passes over a pulley 24, which is journaled in the frame 1, and is in turn connected to and wound about the drum 7. By transmitting power to the drum 7 by means of a clutch mechanism, a pulling action may be imparted to the chain 22, for hoisting the lifting boom 12.

Referring more especially to Figures 2, 3 and 4 it will be noted that the apparatus includes an excavating drag bucket or scoop 25, which comprises the two sections 26 and 27. The two sections are hingedly united, and where they are so connected a pivoting rod 28 is used. Where the sections 26 and 27 are pivotally connected, the ears 29 of the section 26 overlap the ears 30 of the section 27, and through these ears the rod 28 extends, hence pivotally uniting the two sections. An elongated sleeve 31 surrounds the pivoting rod 28, and its ends engage with the opposite faces of the ears 30, there being nuts 32 on the ends of the rod, so as to hold the parts pivotally together.

Bail straps 33 also receive the ends of the rod 28 and the nuts 32 bear against the outer faces of the bail straps to hold them in position. A handle 34 of the bail straps 33 are fastened by bolts and nuts 35 to the section 27 of the drag bucket or scoop. Obviously

when the section 27 opens relatively to the section 26, the bail straps 33 move therewith. The bail straps are reinforced relatively to the section 27 by means of the braces 36, which are connected to the bail straps by means of nuts and bolts 37. The braces 36 are in turn fastened to the section 27 by nuts and bolts 38. The opposite end portions 39 of the bail straps 33 are extended in parallelism, and journaled on a pin 40 between the extremities of the portions 39 is a pulley 41.

Fastened by means of nuts and bolts 42 and 43 to the opposite sides of the section 26 of the drag bucket or scoop 25 are additional bail straps 44. The end portions 45 of the bail straps 44 are extended in parallelism, and journaled on a pin 46 between the extremities of the portions 45 is a pulley 47. A transversely disposed brace 48 fastened by nuts and bolts 49 to the bail straps 44 relatively reinforce the bail straps.

A cable 50 is attached to a bail strap 51 which is connected to the pin 46, and passes over a pulley 52, which is carried by the frame. This cable 50 passes over the pulley 53 and is connected to the drum 8 and wound thereabout.

Connected at 54 to the boom is a cable 55, which passes over the pulley 47 and then over the pulley 15, and thence over the pulley 41. This cable 55 then passes over the pulley 16 and thence over the pulleys 56 and 57, and is then connected and wound about the drum 9. By means of this cable the section 27 of the drag bucket or scoop is manipulated to a closed position, and when the drag bucket or scoop is raised this cable is slackened, when the bucket is opened by means of a chain 58.

The short chain 58 is connected by a fastener 59 to the section 27 of the drag bucket or scoop, and is in turn connected to a cable 60, which passes over the pulley 17, and thence over the pulleys 61 and 62, and is then connected to and wound about an additional drum 63 on the shaft 5. When the drum 63 is operated, and the cable 55 slackened, and the drag bucket hoisted, the cable 60 having been slackened, the cable 60 pulls upon the section 27 and opens the same, thereby acting to dump the contents of the bucket.

When excavating the drag bucket or scoop is lowered and assumes a position shown in Figure 2, in which case the cable 55 is taken up or tightened for holding the section 27 of the scoop closed, then the drum 8 is operated or put in gear with the shaft 5, imparting a pulling action on the cable 50, which will cause the scoop to dig its scooping end or nose into the ground, hence excavating. As soon as the scoop is filled, the cable 50 is allowed to slacken slightly,

in which case the scoop is hoisted by means of the cable 55 with the boom to a position shown in Figure 1. The cable 55 is then held on the drum in a tightened position, 5 and the drum is stopped to permit the cable 60 to open the section 27 of the scoop, allowing the discharge of the material. In order to move the boom in a vertical plane 10 tiltably, the hoisting chain 22 is operated by means of the drum 7.

It will be noted that the body section of the bucket is so shaped, that when it is disposed in the position shown in Figure 2, its digging or excavating nose 67 will dig into 15 the ground, the inclined wall 68 will then assume an approximate acute angle to the surface of the ground. Furthermore it will be noted that the section 27 constitutes what may be termed as the rear bottom section, 20 and where the sides of the two sections of the bucket come together, the adjacent edges of the side of the two sections are so curved, that when the bucket is in a hoisted position, they are disposed forwardly and down- 25 wardly, namely toward the frame of the apparatus, so that when the bucket is in an excavating position, the section 27 will act as a top for the excavating body section, and since the bail straps 33 extend beyond 30 the pivot rod 28, the cable 55 will act to hold the section 27 closed. Obviously when the bucket is hoisted to the position shown in Figure 1, the bucket may open by separating the sections without contacting with 35 the top of a dump car, over which the bucket becomes positioned, for dumping that which has been excavated. When the bucket is positioned over the dump car, the section 27 may open without contacting with 40 the top of the dump car. The bucket when so arranged over the dump car is disposed in a very close position to the top, hence the reason for constructing and operating the rear bottom section so that it will not contact 45 with the top of the car.

The invention having been set forth, what is claimed as being useful is:

1. In an excavating apparatus, the combination with a lifting boom, of a supporting frame therefor, an excavating drag bucket comprising an excavating or digging body section and a rear bottom dumping section, 50 said sections being hingedly connected adjacent their upper edges, whereby when the bucket is in a digging or excavating position the rear bottom section may assume a position, constituting the rear top of the bucket over the excavating section, and when the bucket is hoisted with the lower 55 portion of the bucket in close position to the top of a dump car the rear bottom section may swing open without contacting with the dump car, means for dragging and digging the nose of the excavating body section 60 into the ground, means under tension to

hold the rear bottom section closed when the body section is excavating and constituting means for hoisting the bucket when filled, the dragging means having been slackened, and means for opening the rear bottom section after the hoisting means has been partially slackened, whereby the contents of the bucket may be discharged. 70

2. In an excavating apparatus, the combination with a lifting boom, of a supporting frame therefor, an excavating drag bucket comprising an excavating or digging body section and a rear bottom dumping section, 75 said sections being hingedly connected adjacent their upper edges, whereby when the bucket is in a digging or excavating position the rear bottom section may assume a position, constituting the rear top of the bucket over the excavating section, and when the bucket is hoisted with the lower portion of 80 the bucket in close position to the top of a dump car the rear bottom section may swing open without contacting with the dump car, means for hoisting the bucket, means for cooperatively connecting with the 85 bottom and operatively attached with the rear bottom section for opening the same, 90 whereby the contents may discharge.

3. In an excavating apparatus, an excavating drag bucket comprising an excavating body section and a rear bottom dump section, a bail connected to the body section and assuming a vertical position when the bucket is hoisted, means pivotally uniting the two sections adjacent their upper edges, 95 whereby the rear bottom section may open rearwardly and upwardly, when the bucket is in a close position to the top of a dump car, a bail connecting with the pivot between the two sections and in turn connecting with the dumping section, the last mentioned bail extending beyond the pivot, whereby an upward pull upon the extended part of the second bail will hold the dumping section closed, when the bucket is in an 100 excavating position, and means operatively connecting with the extended part of the second bail to hold the dumping section closed. 110

4. In an excavating apparatus, an excavating drag bucket comprising an excavating body section and a rear bottom dump section, a bail connected to the body section and assuming a vertical position when the bucket is hoisted, means pivotally uniting 115 the two sections adjacent their upper edges, whereby the rear bottom section may open rearwardly and upwardly, when the bucket is in a close position to the top of a dump car, a bail connecting with the pivot between the two sections and in turn connecting with the dumping section, the last mentioned bail extending beyond the pivot, whereby an upward pull upon the extended part of the second bail will hold the dump- 120 125 130

ing section closed, when the bucket is in an excavating position, and means operatively connecting with the extended part of the second bail to hold the dumping section closed, means operatively connecting with the first bail for hoisting the bucket, means operatively connecting with the first bail for dragging the bucket, and means operatively connecting with the rear dumping section to open the same, when the rear bottom section closing means are partially slackened.

5. In an apparatus for the purpose indicated, an excavating drag bucket comprising an excavating body section having the forward inclined digging wall, which when the bucket is disposed in an excavating position, operatively digs its nose into the ground, a rear bottom dumping section substantially opposite the digging wall, means adjacent the upper edges of both sections for hingedly uniting the two sections, whereby the rear bottom dumping section constitutes the top when the bucket is in an excavating position, said rear bottom section being so constructed and pivotally united to the body section, as to permit the rear bottom section to swing rearwardly and upwardly when the bucket is in a close position to a dump car, whereby the bottom section will not contact with the car when opened.

6. In an apparatus for the purpose indicated, an excavating drag bucket comprising an excavating body section having the forward inclined digging wall, which when the bucket is disposed in an excavating position, operatively digs its nose into the ground, a rear bottom dumping section substantially opposite the digging wall, means adjacent the upper edges of both sections for hingedly uniting the two sections, whereby the rear bottom dumping section constitutes the top when the bucket is in an excavating position, said rear bottom section

being so constructed and pivotally united to the body section, as to permit the rear bottom section to swing rearwardly and upwardly when the bucket is in a close position to a dump car, whereby the bottom section will not contact with the car when opened, means operatively connecting with the bottom section at a point intersecting or passing through the pivots of the two sections, for holding the bottom section closed when the bucket is in an excavating position.

7. In an apparatus for the purpose indicated, an excavating drag bucket comprising an excavating body section having the forward inclined digging wall, which when the bucket is disposed in an excavating position, operatively digs its nose into the ground, a rear bottom dumping section substantially opposite the digging wall, means adjacent the upper edges of both sections for hingedly uniting the two sections, whereby the rear bottom dumping section constitutes the top when the bucket is in an excavating position, said rear bottom section being so constructed and pivotally united to the body section, as to permit the rear bottom section to swing rearwardly and upwardly when the bucket is in a close position to a dump car, whereby the bottom section will not contact with the car when opened, means operatively connecting with the bottom section at a point intersecting or passing through the pivots of the two sections, for holding the bottom section closed when the bucket is in an excavating position to open the same when the first means is slackened.

In testimony whereof we hereunto affix our signatures.

JOHN C. MUNDY.
HARRY T. WILSON.
